PAGE 2

FIG3

FIG4

FIG.5

FIG.6

FIG. 1 is a top plan view of the reflector showing the new design;

FIG. 2 is a side elevation view thereof;

FIG. 3 is a bottom plan view thereof;

FIG. 4 is a sectional view thereof taken on line 4—4 of FIG. 1;

FIG. 5 is a sectional view of the reflector mounted on an industrial safety light which is shown in broken lines for illustrative purposes only; and

FIG. 6 is a perspective view of the reflector.

I claim:

The ornamental design for a reflector for an industrial safety illuminating device, as shown and described.
